UNITED STATES PATENT OFFICE.

GUSTAVE A. KROHN, OF COARSEGOLD, CALIFORNIA.

IGNITION DEVICE FOR INTERNAL-COMBUSTION ENGINES.

1,226,083.

Specification of Letters Patent.

Patented May 15, 1917.

Application filed February 7, 1916. Serial No. 76,507.

To all whom it may concern:

Be it known that I, GUSTAVE A. KROHN, a citizen of the United States, and a resident of Coarsegold, Madera county, State 5 of California, have invented a certain new and useful Ignition Device for Internal-Combustion Engines, of which the following is a specification.

The invention relates to apparatus for 10 varying the time of the ignition spark in accordance with the speed of the engine.

An object of the invention is to provide 15 an ignition timing device for Ford engines which may be readily attached to the engine without any additional means of attachment and without permanently removing any of the ignition timing apparatus now employed on the engine. In accordance 20 with my invention, I simply remove the commutator, insert the automatic timing device of my invention and replace the commutator, so that the automatic device may be quickly and cheaply applied.

The invention possesses other advantages, 25 which, with the foregoing, will be set forth at length in the following description where I shall outline in full that form of the invention which I have selected for illustration in the drawings accompanying 30 and forming part of the present specification. It is to be understood that I do not limit myself to the showing made by the drawings and description as I may adopt many variations in the invention as set 35 forth in the appended claims.

Referring to said drawings:

Figure 1 is a vertical section of my device for applying a speed controlled ignition timing means to a Ford engine, the 40 section being taken on the line 1—1, Fig. 2.

Fig. 2 is a vertical section taken on the line 2—2, Fig. 1.

Fig. 3 is a front view, partly broken away, of the commutator and its inclosing 45 casing.

The engine case 3 of the Ford engine is provided at the front with a circular shoulder 4 which is concentric with the timing shaft 5 which projects through the case. 50 The commutator is ordinarily mounted directly on this shoulder and the brush arm is secured directly to the shaft 5. The commutator comprises a ring 6 of insulating material in which are embedded the commutator segments 7 which are connected to 55 corresponding terminals 8. The ring 6 is

mounted within the metallic case 9 which seats on the shoulder 4 and is held pressed against the shoulder by a flat spring 12 secured to the engine case and contacting with the outer closed end 13 of the case. The case is provided with an arm 14 to which lever 15 is connected, for manually rotating the case to vary the time of ignition. My invention contemplates the interposition 65 between the timing shaft and the brush holder, of means for automatically varying the position of the brush with relation to the timing shaft in accordance with the variations in the speed of the engine. 70

In accordance with my invention, I remove the commutator case 9 from the shoulder 4 and remove the contact holder from the timing shaft 5. The contact holder in Ford engines is secured to the timing shaft 75 by a pin 16. The automatic timing device of my invention comprises a bushing 17 provided with a flange 18. The bushing is slipped over the shaft 5 and is secured thereto by the pin 16 which formerly held the 80 contact holder. Pivoted to the flange 18 at diametrically opposite points are governor weights 19 which are moved outward about their pivots by the centrifugal force imparted by the rotating shaft. The weights 85 are connected together by a spring 21 so that the amount of their outward displacement varies with the speed of the shaft. Formed integrally with each weight and arranged concentrically with its pivot is a 90 gear segment 22, the two segments meshing with a gear 23 formed on the sleeve 24 which rotatably engages the bushing 17. Displacement of the weights 19 thereby causes a partial rotation of the sleeve on 95 the bushing. On the outer end of the sleeve is formed a brush holder 20, carrying the brush 25. The sleeve is held against longitudinal displacement on the bushing by the extension nut 26 which extends into the 100 bushing and engages the thread on the end of shaft 5.

On account of the interposition of the governor, the brush 25 is displaced from the engine casing a greater distance than 105 the contact is on ordinary engines and in order that the same commutator may be used, means are provided for supporting the commutator in position to be engaged by the brush. This I have accomplished 110 by providing an extension ring 27 having on one side a shoulder 28 which fits on

shoulder 4 and on the other side a shoulder 29 of the same diameter as shoulder 4, on which the casing 9 fits. The distance between the shoulders 28 and 29 is equal to 5 the distance that the brush is displaced owing to the interposition of the governor. The case 9 is held in place by the same spring 12 which formerly held it in place. Since the governor operates to vary the 10 time of the spark in accordance with the speed of the engine, manual control of the spark is now inadvisable and the lever 15 is secured in position so that the commutator may not be moved. The position of 15 the commutator is adjusted by hand, so that proper ignition timing at high or low speeds is obtained and then it is secured in position and the variation in timing is accomplished by the governor.

20 It has been shown that the commutator may be employed and that no additional holding means therefor are necessary. The commutator and contact holder are removed, the governor and extension ring are placed 25 and then the commutator is reset on the extension ring. It is, of course, understood that the governor operates to advance the spark as the engine speed increases and to retard the spark as the engine speed decreases.

I claim:

1. An ignition timing device for internal combustion engines comprising a driving member, a driven member, a centrifugal 35 element forming an operative connection between said members and adapted to vary the angular relation of the members by changes in its position, a contact arranged on the driven member, a stationary commutator surrounding said contact and engaged thereby, a casing containing the commutator, an extension ring fixedly engaging the engine casing and surrounding said centrifugal element, a shoulder on said ring 40 engaged by said commutator casing and means for holding said casing on said ring.

2. In an internal combustion engine having a casing and timing shaft extending therethrough and a shoulder on the casing 45 concentric with said timing shaft, a contact holder, a centrifugal element forming an operative connection between said timing shaft and contact holder and adapted to vary the angular relation of the con-

tact holder with respect to the shaft by 55 changes in its position, an extension ring fixedly engaging the shoulder on the engine casing, a shoulder on the extension ring, a commutator casing engaging the shoulder on the extension ring, a commutator in said casing in position to be engaged by the contact in said contact holder and a spring for pressing said commutator casing against said ring.

3. The combination with an internal combustion engine having a casing provided with a circular shoulder, a timing shaft extending through the casing and concentric with said shoulder, a commutator, a casing surrounding the commutator adapted to seat on said shoulder and a contact arranged to engage the commutator, of an extension ring arranged between the engine casing and the commutator casing arranged to seat on the shoulder on the engine casing 75 and having a shoulder of the same diameter on which the commutator casing seats and a centrifugal element forming an operative connection between the timing shaft and the contact adapted to vary the angular relation of the contact with respect to the timing shaft by changes in its position.

4. The combination with an internal combustion engine having a casing provided with a circular shoulder, a timing shaft extending through the casing and concentric with said shoulder, a commutator, a casing surrounding the commutator and adapted to seat on said shoulder, of a flanged bushing secured to the timing shaft, governor 90 weights pivotally attached to the flange of said bushing, a sleeve surrounding the bushing, a gear on said sleeve, gear segments on said governor weights meshing with said gear, a contact carrier secured to said 95 sleeve, a contact carried by said carrier, an extension ring engaging said shoulder and provided with a shoulder on which said commutator casing seats, a nut engaging said shaft and holding said sleeve on said bushing and means pressing the commutator casing against said ring.

In testimony whereof, I have hereunto set my hand at Raymond, California, this 28th day of January, 1916.

GUSTAVE A. KROHN.

In presence of—

E. L. McCAPES.
